US00D833482S

(12) **United States Design Patent** (10) **Patent No.:** **US D833,482 S**
(45) **Date of Patent:** **** Nov. 13, 2018**

(54) **ROCKER ARM**

(71) Applicant: **Eaton Corporation**, Cleveland, OH
(US)

(72) Inventors: **James Edward McCarthy, Jr.**,
Kalamazoo, MI (US); **Matthew Vance**,
Kalamazoo, MI (US); **Guruprasath
Alagarsamy**, Tamil Nadu (IN)

(73) Assignee: **Eaton Corporation**, Cleveland, OH
(US)

(**) Term: **15 Years**

(21) Appl. No.: **29/609,402**

(22) Filed: **Jun. 30, 2017**

Related U.S. Application Data

(63) Continuation-in-part of application No. 29/532,970,
filed on Jul. 13, 2015, now Pat. No. Des. 791,190.

(57) **CLAIM**

The ornamental design for a rocker arm, as shown and described.

DESCRIPTION

FIG. 1 is a first perspective view of a rocker arm showing the new design.

FIG. 2 is a second perspective view of the rocker arm of FIG. 1.

FIG. 3 is a top view of the rocker arm of FIG. 1.

FIG. 4 is a bottom view of the rocker arm of FIG. 1.

FIG. 5 is a first side view of the rocker arm of FIG. 1.

FIG. 6 is a second side view of the rocker arm of FIG. 1.

FIG. 7 is a first end view of the rocker arm of FIG. 1; and,

FIG. 8 is a second end view of the rocker arm of FIG. 1.

The broken line showing portions of the rocker arm form no part of the claimed design.

1 Claim, 7 Drawing Sheets
